CLAIM

An ornamental design for a ventilating hood for an electroplating tank, substantially as shown and described.

DESCRIPTION

FIG. 1 is a perspective view of a ventilating hood in accordance with our new design;

FIG. 2 is a cross-sectional view taken along the line 2—2 of FIG. 1;

FIG. 3 is a front elevational view, the rear elevational view being plain; and

FIG. 4 is a reduced scale bottom plan view.
